DISPLAY STAND

Lee Brunner, Elmhurst, N. Y.

Application November 25, 1949, Serial No. 6,251

Term of patent 14 years

(Cl. D80—9)

To all whom it may concern:

Be it known that I, Lee Brunner, a citizen of the United States, residing in Elmhurst, in the county of Queens and State of New York, have invented a new, original, and ornamental Design for a Display Stand, of which the following is a specification, reference being had to the accompanying drawing, forming part thereof.

Fig. 1 is a front perspective view of a display stand showing my new design;

Fig. 2 is a front perspective view of the display stand in a partially folded position; and

Fig. 3 is a perspective view thereof in a folded position.

The rear of the display stand is substantially plain.

I claim:

The ornamental design for a display stand, substantially as shown and described.

LEE BRUNNER.
